METAL WINDOW UNIT COMPRISING A FRAME AND REMOVABLE SLIDING SASH

Nathan Lewis Stritzler, Westfield, N. J.

Application September 14, 1953, Serial No. 379,865

6 Claims. (Cl. 160—90)

This invention relates to a window unit comprising a frame and a plurality of sliding sash and relates more particularly to a novel unit which may be constructed entirely of metal except for the mounting elements for the sliding sash, which latter are formed of synthetic plastic material and which afford easy sliding movement of the sash to an adjusted fixed position without the use of any counterbalancing elements or retractible pins.

Metallic window frames and metallic sash have, of course, been known and the usual construction includes metallic trackways for the sash which resemble the wooden trackways of the prior art. The metal frame and sash, however, present the same problem as does the older wooden unit in that the sash either moves too freely or not freely enough, and usually the latter. In view of this uncertain behavior sash weights are required in order to eliminate the possibility of the sash suddenly dropping and mashing one's fingers.

The principal object of the present invention is to provide an improved unit wherein the usual inwardly facing opposed U-shaped trackways are eliminated and in their place the frame is provided with a pair of outwardly facing single track elements for each sash, the sash being provided with generally C-shaped supporting elements which clasp the outer edges of the tracks. Novel means are provided for causing the supporting elements on at least one side of each sash to exert a desired measure of spring-urged pressure on the tracks. The spring loading of the supporting elements in addition to the natural friction which is set up between the metal tracks and the synthetic plastic supporting elements enable the sash to be moved upwardly or downwardly to a desired position where it stays, without the use of counterbalances, until again manually moved to another position.

Another object of the invention is to employ the novel spring loading of the supporting members as a means for effecting easy removal of the sash from the frame for cleaning or for any other purpose.

In the drawings:

Fig. 1 is a front elevation of the inside of a window unit of the present invention, parts being broken away to more clearly show portions of the construction.

Fig. 2 is a horizontal section taken through the window frame and showing portions of all three sash including the screen sash.

Fig. 3 is a broken detailed view, partially in section, of one of the vertical rails of the sash.

Fig. 4 is a broken section of the right-hand rail of the frame, the section being taken on line 4—4 of Fig. 1.

In the embodiment of the invention chosen for illustration in the drawings there is provided a frame for supporting an upper sash 10, a lower sash 11, each of substantially one-half the height of the inside of the frame and being provided with panes of glass 12, and a third sash 13 having a screen 14 therein. This arrangement permits the window opening to be completely closed for winter use and during such period the screen may retain its uppermost position shown in Fig. 1 or it may be removed completely.

For summer use the screen will remain in the frame so that when a screened opening is desired both window sash may be moved upwardly or downwardly and the screen sash moved downwardly or upwardly as the case may be to screen the opening. Each sash has its own trackway and if for any reason four sash should be desired there may be provided four trackways.

2

The frame includes similarly shaped but oppositely facing rails 15, a lower rail 16 and an upper rail 17. The rails are conveniently made from aluminum or other metal which is extruded to provide the cross-sectional contour shown. Each rail includes a pair of spaced, outwardly extending flanges 20 which are received in the corner blocks (not shown) of the window opening. It further includes a first pair of outwardly facing trackways 21 for the screen sash, a second pair of trackways 22 for the lower sash and a third pair of trackways 23 for the upper sash, the latter trackways being formed with inwardly extending flanges 24 which form a water-tight closure with the upper sash as shown (Fig. 2).

The screen includes upper and lower rails 25 and side rails 26, each of which is hollow and is formed from sheet metal suitably bent to provide a generally rectangular cross-sectional contour. The rails are mitered at their terminals and are secured together as by means of staking. One such side rail is shown in Fig. 3 and it includes an intermediate wall 30 which is spaced outwardly from an inner wall 31 having a flange 32. There is thus provided a channel 33 which extends around the inner periphery of the frame to receive the screen which may be secured within the channel by any suitable means.

Fig. 3 also shows one of the sash supporting elements or bearing members 34 which enables the sash to be slideable relative to the trackways of the window frame. This supporting element is mounted for inward and outward movement in an opening 35 in the outer wall 36 of the sash rail 26. It is constructed from a suitable synthetic resin which can be molded to shape or otherwise formed and which permits fairly free sliding movement of the element relative to the trackway while still affording enough frictional resistance to travel thereon, while under the spring tension, to prevent the sash from moving of its own accord due to gravity.

The support has a vertical through bore 37 of generally rectangular shape which receives a wire spring 40 whose curved terminals 41 engage the inner surface of wall 36. Any forces tending to draw the element outwardly of the rail are yieldingly resisted by the spring which contacts the inner wall of the bore at points 42. The support further has a generally C-shaped outer terminal 39 which receives the outer edge of track 21.

These supporting members which are in effect bearing elements may be made from any one of a number of the newer plastic materials formed from natural or synthetic resins. These materials are not as resilient as rubber, which can be expanded or deformed to a limited but desired extent and which seek to regain their original shape and continuously exert pressure against any member tending to resist this return. Material of this kind does not take a permanent set, except when a radical variation in temperature occurs which continues for a period of time. Specifically, nylon has given excellent results as has one plastic formed from tetrafluoroethylene and is currently available under the trade-mark "Teflon."

It was earlier pointed out that these bearing elements are spring loaded on at least one side rail of the sash. Thus it will be seen that the bearing elements at the left-hand end of the screen sash (Fig. 2) is provided with the spring 40 and the spring is omitted from the similarly shaped member at the right-hand end. In this instance the bearing element may be simply cemented or otherwise rigidly secured in the frame recess.

The rails in the other sash 10 and 11 are formed with inwardly facing recesses 44 to receive the glass and otherwise they are provided with the same bearing elements as have been described with reference to the screen sash.

To remove the screen sash from the tracks it is simply necessary to place the fingers on the right-hand vertical rail and move the rail far enough to the right to cause the left-hand movable bearing elements to move outwardly under the bending tension of the springs sufficiently far to enable the right-hand bearing elements to clear the right-hand track.

Another method of removal is shown for the other two sashes, namely, in providing recesses 45 in the tracks and when a bearing element is aligned with this recess it is moved toward the inside of the frame and the

sash is removed without overcoming the tension of the springs.

If desired the upper and lower rails of the frame may be provided with weatherstrip means similar to vertical weatherstrip flange 24 for the outer sash.

While one form or embodiment of the invention has been shown and described herein for illustrative purposes, and the construction and arrangement incidental to one specific application thereof has been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

1. A window unit including a frame formed with upper and lower rails and vertical side rails formed with a plurality of spaced pairs of outwardly facing tracks, and a window sash slidably carried on each pair of said tracks, each sash including a generally rectangular frame of lesser height than the frame, each vertical rail of each said sash having a C-shaped bearing element extending outwardly therefrom and which grasps and rides on the outwardly facing track, the bearing elements on at least one side of each sash being outwardly movable under spring tension.

2. A metal window unit including a frame formed with upper and lower rails and vertical side rails formed with a plurality of pairs of outwardly facing tracks which are spaced inwardly, one from the other, and a window sash slidably carried on each pair of said tracks, each sash including a generally rectangular frame, each vertical rail of each said sash having a generally C-shaped bearing element formed of resilient bearing material and extending outwardly therefrom and which rides on the outwardly facing track, the bearing element on at least one side of each sash being outwardly movable and being spring-urged inwardly and which permits removal of the sash from the tracks when the spring-urged bearing element is moved outwardly.

3. A window unit including a frame formed with upper and lower rails and vertical side rails formed with at least three spaced pairs of outwardly facing single tracks, and a window sash carried on each pair of said tracks, each sash including a generally rectangular frame of substantially one-half the height of the frame, at least one of which sash supports a window screen and the remaining sash supports a pane of glass, each vertical rail of each said sash having at least two generally C-shaped bearing elements extending outwardly therefrom

and which ride on the outwardly facing tracks, the bearing elements on at least one side of each sash being outwardly movable under spring tension.

4. A window unit formed largely of metal and including a frame formed with upper and lower rails and vertical side rails provided with at least three spaced pairs of outwardly facing tracks, and a window sash carried on each pair of said tracks, each sash including a generally rectangular frame of lesser height than the frame, each vertical rail of each said sash having at least two generally C-shaped bearing elements formed of nylon extending outwardly therefrom and which ride on the outwardly facing tracks, the bearing elements on at least one side of each sash being outwardly movable under spring tension.

5. A window unit including a frame formed with upper and lower rails and vertical side rails formed with a plurality of pairs of outwardly facing single tracks, and a window sash carried on each pair of said tracks, each sash including a generally rectangular frame of lesser height than the frame, each vertical rail of each said sash having at least one generally C-shaped bearing element formed of resilient plastic material which extends outwardly therefrom and which rides on the outwardly facing track, at least one vertical rail having a bearing opening in which the bearing element is slidably mounted and a spring urging the movable bearing element inwardly of the sash.

6. A window unit including a frame formed with upper and lower rails and vertical side rails formed with a plurality of spaced pairs of outwardly facing single tracks, and a hollow window sash formed of sheet metal slidably carried on each pair of said tracks, each sash including a generally rectangular frame of lesser height than the frame, the outer face of each vertical rail of each said sash having an opening therein and a generally C-shaped bearing element mounted therein and extending outwardly therefrom, said bearing elements riding on said tracks, the bearing element on at least one side of each sash being outwardly movable, and a spring urging the same inwardly.
